TABULATING MACHINE

Eugene M. La Boiteaux, Washington, D. C.

Application November 12, 1935, Serial No. 49,408

25 Claims. (Cl. 235—91)

This invention relates to perforated record-controlled tabulating machines, and particularly to that type of machine used for recording and compiling information indicated by holes punched in record cards, the information being transferred to a system of accumulators or wheels by means of analyzing devices cooperating with holes, and causing a chain of elements to be set in motion to thereby properly tabulate and record the information indicated by the holes in the card. The type of tabulating machine now in general use has certain disadvantages, particularly the electrical portion of such machines, wherein variations in resistance coils and various other inconsistencies occur when electric current is utilized in high precision work. This is because in any source of electrical power, regardless of community, fluctuations in voltage occur which cause the difficulties just mentioned. In usage, the resistance of the wires varies and this often sets up a circuit that is too weak to properly actuate the wheels in accordance with the speed at which the machine is operated. The selective or analyzing means used in the most advanced machines at the present time are generally made up of a plurality of wires of a comparatively small diameter, and it is very easy for these wires to bend or break, in which case one or more wires catch the card itself and tear it or cause it to move from its desired path. This necessitates shutting down the machine to remove or straighten out the card if the card continues on through, as inaccuracy in tabulation may be caused by such continued movement of the card. The points of these wires often become burnt or carbonized; hence the voltage of the current supposed to flow through them is changed or varies and the proper timing of operative movements of the machine parts is interfered with. Magnets must be used with this type of machine and the fluctuations of the current, due to overloading, etc., will frequently cause their operation to be irregular. The mechanism of the electrical machines is very involved and expensive and the entire machine is unnecessarily heavy and cumbersome.

The above are some of the reasons why it is highly desirable to eliminate the electrical contact portion and to this end I have produced a tabulating machine that is mechanical throughout, the only use I make of electricity being as a source of power. Of course, any suitable source of power will do, but I prefer the electrical current.

Another object is to simplify the resetting of

the accumulators of the recording means. This is now accomplished in other machines by reversing the wheels two or more revolutions from their normal direction of rotation, but in my new device in resetting, the wheels are rotated but once and in their normal direction which adds to the efficiency of operation and eliminates the necessity of the additional mechanism for reversing the wheels. Another and further object of the invention in connection with resetting, is the provision of normal means by which the analyzing elements are mechanically reset after each cycle of operation.

A still further object of the invention is to provide a novel means for resetting the wheels whereby they are reset in a much shorter time than heretofore and which is done automatically after each "print". However, this may also be accomplished manually and expeditiously, as may be desirable when a card "slips" time in moving through the machine, and thus interferes with the proper operation thereof. In such a case it may be desirable to stop the machine, which upon starting up again and upon the manual manipulation of the resetting device, all of the counters will be reset at zero.

It is my belief that the principles and elements involved in resetting and analyzing, in accordance with my invention, are broadly new.

In the drawings illustrating my invention—
Fig. 1 is a top plan view of the entire machine.

Fig. 2 is a side view, partly in section and partly in elevation, looking at the left hand side of the machine.

Fig. 3 is a front elevation of the card feeding apparatus.

Fig. 4 is a view taken on the line 4—4, Fig. 1, partly in section and partly in elevation.

Fig. 5 is an elevation with the left hand side plate removed and is taken on the line 5—5 of Fig. 1.

Fig. 6 is an elevation, looking from the left hand side of the machine, showing the gearing located on the right hand side and taken about on the line 6—6 of Fig. 1.

Fig. 6a is a detail end view of the rear portion of the machine, to be read in connection with Fig. 6, looking toward the rear of the machine, or in the direction of the arrow, intended to more clearly show the relative position of certain gears and rollers, and the manner of supporting the latter yieldingly in contact with each other.

Fig. 7 is a detail view of the analyzing rolls and lever when the head of a lever is about to penetrate an opening in a card.

Fig. 8 is a view similar to Fig. 7 and shows the analyzing lever seated in one of the analyzing recesses.

Fig. 9 is a detail view of the analyzing roll, partly in elevation and partly in section.

Fig. 10 is a section of the analyzing lever bearing block taken on line 10—19 of Fig. 4.

Fig. 11 is a view partly in section and partly in elevation of parts of the machine, and taken on the line 11—11 of Fig. 1.

Fig. 12 is a detail view showing the position of the analyzing rolls and levers when there is no card passing between the rolls.

Fig. 13 is a view, taken on line 13—13, Fig. 1, illustrating the drive for part of the gearing in Fig. 6 and other elements.

Fig. 14 illustrates part of the detail of the "no-card" control.

Fig. 15, taken on the line 15—15 of Fig. 1, looking from the right hand side of the machine, illustrates further details of the "no-card" control.

Fig. 17 is a detail view taken on the line 17—17 of Fig. 15.

Fig. 18 is taken on the line 18—18 of Fig. 1 and illustrates the analyzing and counting mechanism, with the pivot block of the counting mechanism shown partly in elevation and partly in section.

Fig. 18a is a plan view of a record card, two columns of which would be analyzed by the push rod arrangement or set-up shown in Fig. 1.

Fig. 19 is a view taken on the line 19—19 of Fig. 1 and illustrates additional details of the counting mechanism.

Fig. 20 is a side view of the front portion of the machine, showing some of the elements in section and some in elevation, with the side plate removed from the swinging section.

Fig. 20a is a detail side view and partial section of a cam and clutch disk mechanism illustrated in Fig. 20, looking in the direction of the arrows 20a.

Fig. 21 is a view, substantially the same as Fig. 20, but showing some of the elements in different positions.

Fig. 22 illustrates the counting mechanism of Figs. 18 and 19 assembled, and the position of certain cams during the reset operation.

Fig. 23 illustrates, in section, the operation of the latching and paper release mechanism.

Fig. 24 is a top plan view of a portion of Fig. 23, the paper tension roll and shaft.

Fig. 25 is a side elevation of the front portion of the right hand side of the machine.

Fig. 26 is a view, partly in section and partly in elevation, taken on line 26—26 of Fig. 27 and illustrates part of the mechanism for starting and stopping the machine.

Fig. 27 is a part section and part elevation of the start and stop mechanism, taken on the line 27—27 of Fig. 25 and is partly diagrammatic.

Fig. 28 is a detail of the feed roll, and

Fig. 29 is an elevation taken on the line 29—29 of Fig. 28.

General

When the "back" of the machine is referred to, it means the end at which the cards are deposited after the information thereon has been indexed or tabulated by passing under the analyzing roll, and "front" refers to the end at which the tabulating is done.

Number 1 refers to the left-hand side plate of

the machine and 2 to the right-hand side plate, the side plates resting upon and being secured to a suitable base A. The cards are placed in a hopper 3 from where, by means of the reciprocating feeding plate hereinafter described, they are fed to the cylindrical roll 5 which has circumferentially arranged therein a plurality of rows of oblique sided cam recesses. This roll which is shown in detail in Fig. 9 and to be hereinafter described, cooperates with another roll under it 10 to take the information from the card and to continue the movement of the card to another set of comparatively narrow rollers 6 and 7 (Fig. 1) that also have a set of corresponding rollers thereunder whereby the card is moved under the 15 guides 8 and caught by the rollers 9 and 10 carried by the shaft 11. These rollers also have corresponding rollers under them, all rollers on the right-hand side plate being shown in Fig. 5. The guides 8 may be placed at whatever intervals are 20 found expedient, depending on the width, texture and other qualities of the records. Numeral 12 designates an upwardly-inclined ledge to assist in the stacking of the cards by lifting the rearward edge of the incoming card under the forward edge 25 of the card or cards that have already been stacked, a stacked card being positioned so that it will overhang the ledge 12 sufficiently to have the incoming card slide under them.

The machine is made fast to its base A by 30 means of any suitable number of bolts 21 that pass through the flanges 22 and 23 of the side plates 1 and 2.

In Fig. 1, showing a plan view of the hopper, there is the side plate 2 having cut therein the 35 recess 25 for the reception of the lifting plate 26 which has therein an opening 27 for the purpose of allowing clearance for a finger of the hand when the cards are placed in or removed from the feeding hopper. At the forward and rearward 40 sides of the hopper are guides 28, 29, 30 and 31, respectively, and in addition there may be guides 32 and 33 on the sides. All of these guides may extend to any desirable height above the plates 34 and 35 of the hopper. A detailed description of 45 the operation of the feeding plate and connected parts will be found in connection with the description of Figures 3 and 4. The knives on the feeding plate 24 move the edge of a card under the roll 5 and its complement below, at which point the data 50 is taken from the card. As the card continues its rearward movement its rear edge is caught by the rollers 6 and 7 and their complements, and continued in its path under the guides 8 until the rear edge is caught by the rollers 9 and 10 by 55 which it is forced to slide up the incline 12 and partially under the cards already in the receiving hopper 36, the movement of the card which brings it to its final position in the stack being caused by a means that will be presently described.

The rollers 9 and 10 are rigid on the shaft 11 rotatably mounted in the bearing 37, there being a similar bearing on the left-hand side that is hidden from view by the ledge on the upper part of the side plate 1. At the forward ends of arms 65 38 are bearings 39 positioned on the non-rotatable shaft 40. The rollers 6 and 7 are rotatably mounted on stub shafts and are held down on their supports on the cards by means of the springs 41 and 41a, one end of each of which is 70 fastened to brackets supporting the rollers on the roller supports, which will be later described in detail; the other spring 41 being fastened to any suitable projections as 42 and 43. The operation of the sets of rollers just described is more 75

clearly shown in Fig. 5 and will be described in detail in connection therewith. At the extreme rear end of the machine is a back plate 44 against which the cards may be stacked. In the lower plate 45 of the hopper 36 a cut-out portion 46 may be provided so that the cards may be conveniently lifted therefrom.

The portion of the machine above described operates with accumulator mechanism 53 by means of the push rods 54, some of which, as indicated at 51 and 52, may be bent or curved at the proper angle to conform to the difference in width of the analyzing and tabulating portion of the machine, there being a push rod 54 for each active numeral wheel assembly. Others of the push rods according to their grouping with relation to the tabulating mechanism, will be differently formed, for instance, those arranged at the center of the machine or substantially so, will be practically straight, while those off to the sides will be bent or formed like those shown in the drawings, Fig. 1. The accumulator mechanism is supported by the side supports 55 and 56, as is a cross member 57 to which may be attached in any suitable manner a safety member 58 which is positioned over the forward ends of the push rods 54 in order to prevent their ends from becoming dislodged from their rocker arms or actuators to which they are removably attached. A sprocket and chain drive 59 operates a series of gears and a shaft, not shown in Fig. 1, but which will be particularly described in connection with Fig. 25.

The printing mechanism, best illustrated in Figs. 20, 21 and 25, is arranged so that it may be swung forwardly from the machine toward the operator in order that the operator may view whatever has been printed on the sheet. This section which contains important elements of the printing mechanism is released by pressing down on either or both of the thumb pieces 60 and 61 of the latches 62 and 63 which are pivoted at 64 and 65, thus raising the rear ends 66 and 66a off of the pins 67 and 67a. There is a shaft 68 which may carry any desirable number of rollers, spaced conveniently, the rollers being pressed against the paper roll 69 to hold the paper or record sheet that passes over the roll in smooth condition. The latches 62 and 63 perform the additional function of releasing the tension of the rollers on the paper through the medium of a lost motion device which is shown and described in Figs. 23 and 24. The shaft 68 is mounted in bearings on the side plates 71 and 72. The roll 69 may be turned by either or both of the knobs 74 and 75 and the ribbon reverse mechanism 76 may be positioned in any convenient manner. A register, for the purpose of counting the cards as they go through, is indicated at 77, and the mechanism that operates it will be referred to later on.

The main purpose of Fig. 1 is to illustrate in a general way the relative positions of the various parts. Fig. 2 is mostly a general view, in elevation, of the left side of the machine. It more clearly illustrates the guides for the hoppers 3 and 36 including the forward guide plate 78 of the hopper 36, which plate being broken away in Fig. 1. The short bolt 79 on left side, and similar bolt 80 on right-hand side support the shaft 40 and prevent it from rotating. Nuts 81 and 82 are threaded on the reduced ends of the studs 42 and 43, while the bolts 83 and 84 support arms to be described in connection with Fig. 6. The other terminals in the side plate 1 are the ends of various shafts and retaining screws for a purpose

to be later described. The cap 87 covers an opening at the end of the cylindrical roll that is directly under the bearing that supports the roll 5.

The safety member 58 extends rearwardly from the cross piece 57 (Figs. 1 and 2) and rests just above the forward ends 91 of the push rods 54. The ends 91 consist of forked or bifurcated portions 92 (Figs. 1 and 18) having pins 93 across the gap of the fork, the pins resting in recesses formed in the upper ends of the rocker arms, 10 later to be more particularly described. On the outside of the plate 55 is a bell-crank 94 having a handle 95 which may be manually operated to reset the numeral wheels to zero.

In the upper portion and at the extreme front 15 of the machine is a means for holding the latches 62 and 63 in latched position, which consists of a barrel or sleeve 97 fastened to the side plate 71 and having a spring located therein to normally urge the plunger 98 upward. The plunger pushes 20 against the under side of the handle 60 and thus locks the latch on the pivot 64, thereby forcing the rear end of the latch down on the retaining pin 67. This arrangement is preferably provided on both sides of the machine. The nu- 25 meral 99 designates a handle for the purpose of disconnecting the pawl and ratchet of the paper roll to permit of its being rotated in either direc- tion.

A portion of the machine which comprises in 30 part plates 71 and 72, pivots and swings on the shaft 101, and in order to retard the movement of this portion and to relieve the operator of the necessity of lifting its entire weight, a retarding means 102 has been provided and is preferably lo- 35 cated on the under side of the machine. It consists of a rod 103 that works through any number of suitable supports 104 and 105, and at appropriate points are collars 106 and 107 which are fastened rigidly to the rod 103, the collar 106 being for the purpose of limiting the forward movement of the rod when it contacts with the support, 104. The collar 107 has at one side a spring 109 pressing against it; the other end of the spring being against the support 105. At the 40 forward end of the rod 103 is connected a sprocket chain 110, the other end thereof being rigidly fastened to a sprocket wheel 111, the sprocket wheel being rigidly fastened to the side plate 71 by any suitable means such as the screws or rivets 112. 45 When the front portion is swung away, the wheel 111 will turn, thus pulling the chain 110, which, in turn, will pull the rod 103. This movement will continue until the collar 106 contacts the support 104 at which point it will stop. The same 50 movement compresses the spring 109, which action takes up part of the weight of the front portion, and when it is desired to return said portion to normal position, the tendency of the spring to expand will assist in the latter operation. It 55 will be observed that the collars 106 and 107 may be moved when the screws 114 and 115 have been loosened and in this manner the distance through which the rod 103 travels may be determined 60 and the tension of the spring 109 may be adjusted 65 to any suitable degree.

The cable 116 indicates a source of electrical power which I prefer to use for solely driving the machine, and legs 117 and 118 may be any conventional supporting means.

Feeding hopper and associated parts

Figure 3 is a front elevation and illustrates, in detail, the construction of the feeding hopper 3. The side plates 1 and 2 have any suitable 75

number of screws 126 and 127 therethrough to hold the assembly in proper position. The cross bar 128 has rearwardly-extending arms 129 and 129a connected to its respective ends as shown in Figs. 15 and 25 and the lifting plate 26 is attached to the cross bar 128 preferably at the center (Fig. 3) in order to lift the cards that are in the hopper 3. The top of this plate is bent at approximately right angles to the vertical portion and its rear end has a cut-away section in which rests a stationary support 130 for the cards to slide over. When what I designate the "no-card" mechanism shown in Fig. 15 is operated, due to the last card having passed between the rolls 5 and 165, or in other words, when there is not a card passing between the rolls, the cross bar 128 will be moved upward, thus raising the plate 26, which in turn, lifts the cards that may be in the feeding hopper above the feeding knives 131 and 131a. As stated above, at the end of a run, the plate 26 will assume its raised position, so that when the next batch of cards is placed in the hopper 3 they will be held out of reach of the knives 131 and 131a until the operator is ready to send them through. The cross bar 128 is manually lowered when the machine is started by the means shown in Fig. 25. The knives 131 and 131a are adjustably fastened to the forward edges of the plate 24 by means of the screws 132 and 133 and the slots 134, 135, their height above the plate being determined by the thickness of the card. The numeral 137 designates an oscillating arm having its upper end connected to the cross bar 138 by means of the link 140. The link 140 is pivoted to the cross bar 138 and the upper end of the arm 137, as indicated by 142. The oscillating arm 136 which is on the opposite side of the machine from the similar arm 137, has its upper end connected to the cross bar 138 by a link 139 and pivot 142 and 143, or similarly to the arm 137 (Fig. 4). These features are shown clearly in Figs. 3, 4 and 5. The cross bar 138 is riveted or otherwise fastened to the under side of the plate 24 and when the arm 137 is moved toward the rear, the knives 131 and 131a will catch the lowermost card and move it rearwardly to a point where the roll 5 and the roll under it will grip the rear edge of the card and continue it in its movement toward the rear of the machine. On the rear plate 144 of the hopper is an adjustable guide 145 which may be moved vertically when the screw 146 has been loosened and it is normally positioned approximately the thickness of the card above the card support 147 from which extends the card-supporting fingers 130, 148 and 149.

Referring to Fig. 4, it will be seen that the oscillating arms 136 and 137 are rigidly fastened to the sleeve 153 on the shaft 151, at their lower extremities by means of the screws 158 and 158a, and may be radially adjusted thereon by that means. There is a reciprocator 159 pivoted to the arm 137 at 160, the other end of the reciprocator being in the form of a sleeve which surrounds an eccentric fast on the revolving shaft 161 (Figs. 5, 6, 11 and 14), whereby the reciprocator 159 is moved backward and forward, thus rocking the arm 137. The cross bar 138 is fastened to the under side of the plate 24 and is shown in Figure 4, said plate being in its foremost position. As the arms 136 and 137 are moved backward or toward the back of the machine, the plate 24 slides in the guides 162 and 162a, a card is engaged by the knives 131 and 131a, is slid over the fingers 130, 148 and 149

(Figs. 1 and 4) under the adjustable guide 145 and the rear edge of the card is then caught by the pair of rolls, one of which is numbered 5. The main body of the card support 147 is fastened to the block 163 that extends substantially across the width of the hopper 3, this block 163 being the element to which are pivoted the numerous analyzing levers to be presently described. The slot 164 in the back plate 144 permits the vertical movement of the adjustable guide 145. 10

The side elevation and partial section shown in Fig. 5 illustrates the complete progress of the card from the feeding hopper 3 to the receiving hopper 36. As a card passes between the rolls 5 and 165, the analyzing roll 5, in cooperation with 15 analyzing levers, indicates the information to be recorded, and transmits it through the push rods 54 to the accumulator wheel mechanism to be described later. The card is then picked up by the next set of narrow rollers 7 and 166. The card 20 slides under the guides 8 and is then caught by the last set of rollers 9, 10 and 167, and as these rollers will not move the card the entire distance into the hopper 36, there is provided a stacker 168 having at its top a raised portion 169 that engages the forward edge of the card and pushes it against the rear plate 144. As explained in connection with Figure 1, the angular edge 12 of the bottom 45 will raise the rear edge of the card so that it will slide under the over-hanging portion of the cards already in the hopper. The stacker 168 moves in two planes—that is, it rocks back and forth and also up and down, and these movements are accomplished in the following manner. The shaft 161 is driven from the motor 35 by any suitable source of power, and rigidly fastened to the shaft is a cam 171 on the periphery of which the roller 172 bears. This roller is positioned in the bifurcated end 173 of the arm 174, mounted on the shaft 175 and is loose thereon. Fast to the shaft is a short arm 176 having one end of the spring 177 attached thereto with its other end attached to the end 173 of arm 174 for the purpose of holding the roller 172 against the cam 171. The stacker 168 is pivoted to the 45 rear end of the arm 179 at 178, and as the cam 171 revolves it raises and lowers the rear arm 179 thus imparting the same movement to the stacker 168, and this motion is synchronized with the movement of the cards, so that the raised portion 169 will be out of the path of the card until the forward edge thereof has gone by the rollers 9, 10 and 167, which have just released a card. The back and forward movement of the stacker is synchronized with the movement of the card 50 by means of the eccentric 180 that is mounted on the shaft 181. The eccentric is revolved with the shaft 181 and by reason of its engagement with the stacker arm, brings about the said backward and forward movement. As the shaft 60 181 revolves, the eccentric 180 is moved backward and forward, thereby imparting an oscillatory motion to the stacker. The stacker is preferably in the form of a frame having two upstanding similar arms 168 connected by the raised 65 portion 169 which is of sufficient width to insure that the cards are pushed evenly into the hopper and properly stacked. The wheel 181, the arms 188 and 189, and the bell-crank lever 190 have to do with the "no-card" control and the re-setting of the push rods 54, and this mechanism will be fully described in connection with Figures 11, 14 and 15. The numeral 182a designates a sleeve which surrounds the eccentric 180, and integral with the sleeve is an arm 182 which ex- 70 75

tends forwardly and has an adjustable connection 183 with the link 184 pivoted at 185 to the upper end of a short curved arm 186 on the stacker 168.

5 *Power transmission mechanism*

The purpose of Figure 6 is to illustrate the manner in which power is applied to the various sets of rollers; how they are arranged to permit passage therebetween of the cards, while pressure is flexibly being applied to them, and the power source of other mechanisms.

By reference to Figures 6 and 6a it will be seen that the shaft 202 has bearings in the said plates 1 and 2 and carries the analyzing roll 5, while the shaft 203 is rotatably mounted in the links 207 and 207a on opposite sides of the machine, the links being pivotally mounted on similar studs 208 projecting from the side plates. Springs 209 and 209a with their lower ends connected with the links and their upper ends connected to pins laterally projecting from the side plates, serve to hold the rollers 5 and 165 in contact with each other, in which position they remain except when 25 the record card is passing between them. Gear wheels 204 and 205 are fast to the shaft 202 and meshing with the gear 205 is an idler gear 206 mounted on a short shaft 210 in the side plate 2, which gear in turn meshes with the drive gear 30 211 on shaft 291, through which shaft and gear the power for driving the upper set of gears is furnished. The gear 204 meshes with a similar gear 206a on the shaft 203, whereby the rolls 5 and 165 are rotated in unison.

35 The upper pair of rolls 6 and 7 and the lower pair 166 (Figs. 1, 5 and 6) are operated by means of the gear 212 meshing with the power gear 211 on shaft 291, the gear 212 and the roller 166 being on the shaft 213, which shaft spans the space 40 between the side plates 1 and 2 and has bearings in the plates. The upper pair of rolls 6 and 7 and gear 214, as well as a similar gear on the left-hand side of the machine are mounted on stud shafts 215 which are located in the hangers 216 45 pivoted as at 217 to the side plates 1 and 2. The hanger 216 is held in lowermost position by the spring 41a that has one end fastened to the upper arm 219 of said hanger and the other fastened to the stud 43 in the side plate 2, and the other hanger 216, adjacent plate 1, is similarly influenced by a spring 41 with one end attached to the hanger and the other to the stud 42 on plate 1. When a card is caught by the roller, the spring will give sufficiently to permit its passage there- 55 between, but at the same time will firmly hold it.

The third set of rollers—that is, those closest to the rear or 10 and 167, work on the same general principle as the middle set and is provided for the same purpose. The rolls 9 and 10 are 60 rigidly fastened to the shaft 11 (Fig. 1), and there is a complimentary set of rolls 167 positioned immediately below them (Fig. 5). At the extremity of the shaft 11 that has a bearing in plate 2 is a gear 222 that is adjacent to the side plate 2. The lower gear 223 is mounted on a shaft 224 that has bearings in the side plates 1 and 2. The gear 223 on the shaft 224 meshes with the idler gear 255 which rotates on the stud shaft 225 on the side plate 2 and is meshed with 65 the motivating gear 227 on the shaft 181, which is driven by shaft 161 (Fig. 13), the power being transmitted to the shafts 11 and 224 by the intermediate gear 225, as will presently be more particularly described. As is the case in the 70 other sets of rollers, provision must be made

to allow clearance for the passage of the card and this is accomplished by having the shaft 11 positioned in the arm 38 that is pivoted at 230, and said arm has fastened to its other end one end of a spring 231 whose upper end is fastened 5 to the stud 43, the spring serving to exert the pressure on the card as it passes between the rolls to properly feed the card. The arm 38 and the spring 231 are duplicated on the left-hand side 10 of the machine or adjacent to plate 1.

It is to be understood that the distance that the gears are moved away from one another by the passage of a card is approximately the thickness of the card and is so small that it will have no appreciable effect on the relation of the teeth 15 of the different gears to each other.

The manner in which the card-feeding mechanism illustrated in detail in Figures 3 and 4 is operated, is also illustrated in Figure 6. The reciprocator 159 connected to the arm 137 at 160 20 has at its other end an eccentric 242 mounted on the shaft 161. This eccentric may be of any conventional type and is operated by means of the gear wheel 243 meshing with the large gear 211 on shaft 291. The arm 189 and the notched 25 disk 187 are for the purpose of resetting the push rods 54 and will be described in connection with Figures 5, 11 and 14.

30 *Analyzing mechanism*

Figures 7, 8 and 9 illustrate certain mechanisms which, so far as I am aware, thoroughly distinguish my invention from the prior art to which it belongs. This particular portion of the machine I believe to be radically new in the perforated card-control tabulating machine art. In Figure 7 is shown the upper roll 5 keyed to the shaft 202 by means of the key 245. This roll is preferably made up of a plurality of hardened steel cam disks 246 having cut in their peripheries 40 the cam-sided recesses 247 and the plain circular spacer-disk 248. These spacer-disks space the cam-disks to conform to the space between the vertical columns of the record card 249, and in number, include all column designations contained on the card. These designations, as usual, may be minutes, names, months, or any other designations that the exigencies of the situation require, or a coding thereof. The analyzing levers 250 have heads 251 thereon which are adapted to protrude through openings like 252 in the card 249, or through the perforations therein, as it is passed between the rolls 5 and 165. It will be observed that there are nine indentations or recesses 247 in the disks 246, the one on the right-hand side corresponding to the digit 1 and progressing toward the left to the digit 9. The cards 249 passing between the rolls 5 and 165 have already had holes punched through them at certain points to indicate certain information in the particular column in which the hole is punched, which is in accordance with the practice when this type of tabulating machine is used. The lower roll 165 is preferably made with a plurality of sections or disks, some of the disks 253 being of a greater diameter than the others; in other words, they alternate with the spacing disks 254 which are of smaller diameter, thus providing clearance for the head 251 and the necessary freedom of movement of the lever 250. When the head 70 251 of the lever 250 enters a hole in the card, the information thereon will be transferred through the push rods 54 to the accumulator mechanism. Due to the angular form of the head 251 and the similar form of the recesses 247, a head 251 is 75

forced down by the rotation of the roll 5, thus recording the data taken from the card. The roll 165 may be made in a solid piece, but it is preferably made as above described and assembled on the shaft 203.

In Figure 7 the head 251 is shown in its lowermost position—that is, just above the disk 254. The pivot block or support 163 in which is held the elongated pivot pin 257 upon which the analyzing levers 250 are pivoted, is common to all of the levers. The block has recesses 258 to permit positioning and movement therein of the levers 250 and also on the block 163 is an anchor 259 attached to the block by any convenient means such as screws 260 which are for the purpose of retaining one end of the spring 261, the other end of which is fastened to the lower arm 262 of the lever 250 at 263, the spring tending to raise the head 251 upward against the card 249 and in position to instantly enter a hole in a card when one becomes available. In this figure the analyzing lever or bell-crank 250 is shown in its inactive position, but is just on the point of protruding through the hole 252 and entering one of the recesses 247, which, in Figures 7 and 8, is the digit 5 recess. When the head 251 is held down due to the absence of holes in the portion of the card passing over it, the various elements will be in the position shown in this figure—that is, the lower arm 262 of the lever 250 is positioned over the rear end of the push rod 54. When the head 251 enters one of the recesses 247 (Fig. 8) the lower arm 262 of the lever 250 will be moved rearwardly and out of the path of upward movement of the rear end of the push rod 54, the upward movement being caused by the spring 264, one end of which is attached to the comb 265 and the other end to the push rod 54, the rear end of the push rod working in the recess 266, there being, it will be understood, a recess in the comb for each push rod, which construction assures the true short vertical movements of the push rods in their operation. After these movements have taken place, the parts will have assumed the position shown in Figure 8, and continued rotation of the roll 5 will produce a cam action by reason of the formation of the recess 241 on the head 251 and push it down to its original position thereby forcing the arm 262 forwardly to actuate the rod 54 to permit the tabulating or accumulator mechanism to operate. After the rod 54 has moved the required distance and immediately after the digit "1" of the record card has passed from between the two rolls, the arms 189 and 189a (Fig. 5) are lowered by the mechanism shown in Figures 11 and 14, thereby moving the comb 265 downward, thus also moving push rod 54 downward so that the arm 262 may be pushed forward to its original position through action of the horizontally positioned plate 267. The actuating elements for this movement are also described in connection with Figures 11 and 14. These movements just described are timed to take place immediately after the rods 54 have been lowered or reset. The numeral 268 designates a base plate which is provided adjacent the rollers 5 and 165 and positioned so as to support the card during its passage through said rolls.

Figure 9 is a view of the upper roll 5, partly in section, there being omitted the greater part of the recess-containing disks and the spacer-disks. The spacer-disks 248, as well as the recess-disks 266, are held compactly together by means

of a retaining collar 269, which is threaded on the threads 270 of the shaft 202. On the other end of the roller there is provided a groove 271, which is between one of the spacer-disks 248 and a collar 272. The "no-card" lever 190 operates freely in the groove 271 between the threaded disk 272 and the adjacent disk 248, and it will be noted that a disk 273 is provided which is of lesser diameter than the associated disks to permit arm 310 of the no-card lever 190 to work therein without touching the disk 273.

At this point I desire to place emphasis on the construction and operation of the improvements shown in Figures 7, 8, and 9, because of my contribution to this art I have eliminated a vast number of parts usually found in machines of this character, increased the efficiency of the machine both as to volume of work turned out and its accuracy, and have reduced the over-all dimensions of the machine by at least two-thirds. The troublesome brushes, magnets, resistance coils and electrical connections have been eliminated. As is evident from Figure 1, the indexing roll 5 may be of any desirable width and diameter to adapt it to analyze cards of various dimensions. Obviously, there must be a plurality of analyzing levers 250, a similar number of push rods 54 and numeral wheel assemblies or wheels in this mechanism, although it is not a necessary requisite that all of them be used at one time. The number of columns to be analyzed on a card is limited only by the number of recessed disks 246 in the roll 5, and a corresponding number of the elements that cooperate with said disks.

Figure 10 is a sectional view of Figure 4 looking in the direction of the arrows and illustrates the manner in which a plurality of levers 250 may be hung on a common pivot 257 (Figs. 7 and 8) in the pivot block 163. The slots 258 are separated by the partitions 274 and the projection 40 of the inclined face 275 is indicated at approximately the center of the block, while the lower side of the pivot bearing for the pin 257 is indicated at 276, the bearings being open end recesses so that the levers 250 may be first mounted on their pivot rod, and the rod and levers simultaneously placed in position.

Resetting mechanism for the analyzing levers

In Figure 11 the mechanism for resetting the analyzing levers 250 is shown in detail. A portion of the card-feeding mechanism already described is shown, as well as the actuating means therefor, which has also been described. On the shaft 161 is a cam 285 upon whose periphery rides a roller 286 located in the rear end of the arm 188, the forward end of the arm being rigidly fastened on a sleeve 290 which is loosely mounted on the revolving shaft 291. Also, on the sleeve 290 is located the upstanding arm 292a having the two-part push bar 293a pivoted to it at 294a, and pivoted to the bar at 295a, is the other section 296 of the bar, a pivotal connection between the parts permitting a straight horizontal thrust of the bar in its movements, and also the slight up-and-down movements which are required of the bar. The push bar carries the plate 267 which is arranged to slide back and forth in the opening 297a in the arm 189a. The analyzing elements shown in this figure are in the same relative positions as they are in Figure 8. The cam wheel 187a having the four elongated notches 298a therein, is located at the right-hand side of the machine, with a similar wheel 187 on the left-hand side. These wheels are fast on the re- 78

volving shaft 291, and running on their peripheries are the rollers 299 that have bearings on studs fastened in the arms 189 and 189a. The rollers 299 are held on the cam wheel 187a by means of the spring 300, one end of which is fastened at 301 to the arm 189a, the other end being fastened at any convenient point such as the bottom of the machine. The spring 302, fastened to the arm 189a at 303 and also to the arm 292a at 304, holds the roller 286 on the cam 285, and normally, holds the plate 267 in its rearmost position, that is, out of reach of the lower arm 262 of the analyzing lever 250. Cam wheel 187a is timed to make one-quarter of a revolution for each card passing between the rolls 5 and 165—in other words, four cards pass through for each revolution of this cam, and when the roller 299 drops into one of the notches 298a the arm 189a will rock on the shaft 395 and the parts carried thereby will drop a distance equal to the depth of a notch in the wheel. The comb 265 which is a part of the arm 189a, will force the rear ends of the push rods 54 down a sufficient distance to allow the lever arm 262 to ride up over the rods and thus be in proper position for a new card, or in the position shown in Figure 7. Timing of the cam wheels 187 and 187a is such that immediately after the rods 54 have been pushed down the cam head 306 will raise the arm 188, thus moving the arm 292a, the push bar 293a and the plate 267 forward, as shown in dotted lines in Figure 14, where the plate contacts the arm 262 and forces it forwardly to assume the position over the rods 54, as shown in Figure 12. Obviously, this movement lowers the head 251 and lowers it to such an extent that it is not only withdrawn from the hole 252 in the card, but is moved completely below the path of the card 249 and will offer no resistance whatever to the entrance of the next succeeding card, but upon entrance of said card it will be released by plate 257 to allow the head 251 to contact the under side of the card. The movements of the two chains of elements just described occur once for each card with the exception that the backward movement of the plate 267 does not take place when there is not a card passing between the analyzing roll 5 and the roll 165. In Figure 12 the analyzing levers 250 are all held in the position shown, by the plate 257 which plate is in the position it assumes when the no-card lever 190 is in its normal position, as shown in solid lines in Figure 14.

Figure 13 illustrates the manner in which the rotating shaft 161 rotates the shaft 181. There is a sprocket wheel 397 rigidly fastened on the shaft 181 and has a sprocket chain 308 thereon which extends over another sprocket wheel 307a positioned rigidly on the shaft 161. This latter shaft is constantly rotating, and, as described in connection with Figure 5, it keeps the shaft 181 rotating in unison with it because the two sprocket wheels are of the same ratio. The manner in which the arm 188 on the sleeve 290 is held in its upper position (shown in solid lines) when the cam head 306 is not holding it up, will be described in connection with the next four succeeding figures.

"No-card" control mechanism

The general operation of the "no-card" control is illustrated in Figure 14, and the details thereof in Figures 15, 16 and 17, and as it is necessary to overlap the description of these figures, all of them will be considered at the same time.

There is a groove 271 in the roll 5 and directly under it in the roll 165 is a similar groove 309; these grooves being arranged to accommodate the rear arm 310 of the no-card lever 190 which is hung on the pivot rod 257 in the pivot block 163. The roll 165 has a plurality of these circumferential grooves 309 extending across its entire length to accommodate the numerous analyzing levers 250, as well as the no-card lever 190, and these grooves are preferably formed by making up the lower roll assembly by alternating disks having different diameters, as illustrated in Figures 6a, 7 and 8. The arm 310 is normally urged to its upper position by means of the spring 311, and when cards are passing between the rolls 5 and 165 they will force the arm 310 down into the groove 309 where it will be held as long as cards are passing over it, because, before the trailing edge of one card has passed completely beyond the arm, the leading edge of the on-coming card will have assumed a position to prevent the arm from being raised. While the arm 310 is being held down it is in the position shown in dotted lines in Figure 14, and when a card fails to come through, it assumes the position shown in solid lines, thereby by moving the lower arm 312 rearwardly from the position shown in dotted lines to that shown in solid lines, and when it takes this position it will be caught by the latch 313 which is the end of the forwardly extending arm 314 which is rigidly fastened to the sleeve 290 mounted on the shaft 291. As long as the arm 312 is in the dotted line position it will be out of the path of the up-and-down movement of the latch which movement is caused by the roller 286 riding on the cam 285. The only point at which the latch 313 is in engagement with the arm 312 is when the cam head 306 has raised the arm 188 to its upper solid line position, thus lowering the forwardly extending arm 314, which constitutes the latch, and these relative positions, as indicated by the solid lines, will be maintained until another card passes over the arm 310 of the no-card lever. The card-feeding mechanism is synchronized with the rolls 5 and 165, and the cams 187 and 285 in such a manner that the leading edge or margin of the incoming card will be picked up just before the first cam recess 247 in the analyzing roll, which represents the digit 9, has reached the lowermost point in the revolution of the analyzing roll, and the recesses for the remaining digits will coincide with the digits, or holes for the digits on the record cards. The arm 314 is on the left-hand side of the machine and the arm 188 is on the right, and there is a slot 315 in the plate 267 to permit rearward movement therein of the arm 312, of the no-card lever 190.

Figure 15, looking from the right-hand side of the machine, illustrates the manner in which the no-card mechanism is operated, and how it is locked in operative position. The arm 310 of the no-card lever 190 is shown in its upper position—that is, in the groove 271 which is the position it assumes when there is no card passing between the rolls 5 and 165 and the same as that shown in solid lines in Figure 14. As previously described, the arm 314 is normally constantly moving up and down, but when the arm 312 is moved to its rear position, the lower end thereof takes a position over the extreme forward latch end 313 of the arm 314 when it is in its lower position and arrests its upward movement, thus holding the roller 286 above the cam head 306. The forward movement of the arm 312 has permitted the pivoted and spring-backed block 316 to

to move its projecting lug 318 away from the curved lever 319 to the position shown in Figure 17. As the arm 136 is continually oscillating it will contact with the lug 318 when arm 312 has reached the rearmost point of its movement, or in its no-card position, shown in Figure 15. The movement of the curved lever 319 which is caused by the contact of arm 136 with the lug 318 is very slight, but it is sufficient to swing the lever 10 on the pivot 320 which is positioned on a boss 321 (Fig. 17) in the side plate 1. This movement is sufficient to move the catch 322 off of the half-moon lug 323 carried by arm 129. When the catch 322 has been moved from the lug 323 the 15 arm 129 and the cross bar 128 will be forced upward by the action of a spring 566 which is positioned on the outside of the plate 2, and will be described in connection with Figure 25. The arm 129 and its complement 129a, which is on the 20 inside of the plate 2, will be described in connection with Figure 25. The arm 129 and its complement 129a, which is on the other side of the machine, are pivoted in the sides, as indicated at 324, Figure 15, and the upward movement 25 thereof is limited in any convenient manner.

The operation of these elements will now be described, starting from the point just prior to the beginning of a card run. At the end of the last run, when the cards cease to pass between 30 the rolls, the operations above described took place and the elements assumed the positions shown in Figure 15. A new batch of cards is now placed in the feeding hopper and the motor is started. A lever 561 described in connection with Figure 25 and rigidly connected with the arm 129a, and, through the cross bar 128, to the arm 129, is pressed to lower these arms 129 and 129a and permit the catch 322 to ride up over the lug 323 and thereby hold the arms in their lowered 40 position. This action lowers the card-lifting plate 26 (Fig. 3) to permit the cards to be fed by the feeding apparatus which is constituted in part by plate 24 and knives 131, and when the first card passes between the rolls 5 and 165 the arm 310 of the no-card lever 190 will be pushed down thus moving the arm 312 forward to the position shown in dotted lines in Figure 14, and lug 328 on the arm 312 presses against the inclined plate 329 which is held to the block 310 by means of 50 the screw 330. This movement rocks the block on the pivot 317 against the tension of the spring 331 and moves the lug 318 flush against the curved lever 319 and out of the path of movement of the arm 136. The parts will then remain in 55 the positions just described until the last card passes from between the rollers 5 and 165 releasing the extreme end of the arm 310, which will then return to the position shown in Figure 15, or to no-card position. The pivot 317 and the block 316 are set in the bifurcated end 332 of the curved lever 319. There is a very short recess 315 (Figs. 14 and 15) in the horizontal plate 267 which is solely for the purpose of permitting movement therein of the arm 312 of the no-card 60 lever, without interference by the plate.

The numeral 313a designates a stop rigidly attached to the forward end of the arm 314 by means of the set-screw 334, and on the side of the stop adjacent the side plate 1 is a pivot screw 335 (dotted lines Fig. 15), which serves as a bearing for the connecting link 336, the upper end of the link being connected at 337 to the arm 338 which is fast on the shaft 339 of the register or counter 71 (Fig. 1). The up-and-down movement 70 of the arm 314 will actuate the link 336.

which in turn, will operate the register through stub shaft 339, for the purpose of counting the cards. As the no-card lever 190 latches the arm 314 out of operative position the register link 336 will also be at a stand-still and will remain so 5 until the next or succeeding card run. Part of the mechanism now to be described in connection with Figures 18 and 19 has been described in connection with Figures 7 and 8; so will be repeated at this point only sufficiently to pick up 10 the continuity. The arms 189 and 189a carry, suspended between them, a slidable plate 267 which is utilized for setting the analyzing levers 250. The lower end 346 of the arm 262 of the analyzing lever normally rests against or very 15 near to the rear end 347 of the push rod 54, and in its forward movement, due to the action of the head 251 being forced downward by a side of the recess 247 in the analyzing roll 5 will move the push rod in a forward direction. The rear end 347 20 is preferably held up by spring 264 which is attached in any convenient manner to the rod and to the comb 265, the comb having numerous recesses 266 in its lower edge into which the ends of the rods extend for the purpose of guiding them 25 during their forward and backward movements. When motion is imparted to the push rod its forward end 348 (Fig. 18) having therein the pin 98 removably set in the recess 349 of the upper end 351 of the rocker arm 352, will rock this arm on the 30 shaft 353, thus moving the lower end 354 downward and rearward, and when this action takes place, the lower end 354 of the rocker arm 352 will force the rear arm 355 of the anchor 356 downward, thus rocking the anchor on the shaft 35 357, thus removing the head 358 which is carried by the upper arm 359 of the anchor 356 from one of the teeth 360 of the disk 361. The toothed disks 361, the numeral disk 362 and the carry and reset disk 363 shown in Figure 19, may 40 be fastened together in any convenient manner, such for instance as by screws, and they are not rigidly fastened to the shaft 364, but are frictionally mounted thereon to rotate therewith when operated during tabulation. 45

When an impulse is given a rod 54, the anchor 356 will be rocked through the rocker arm 352, out of engagement with a tooth on the tooth disk 361, thereby permitting the shaft to pick up the whole numeral wheel assembly and carry it with 50 it until the anchor is released to permit it to return to position to engage another tooth to again hold the numeral wheel assembly against rotation. The anchor is held out of engagement with the numeral wheel by the rocker arm 352 55 until it is released by the downward movement of the comb 265, which permits rod 54 to be pulled rearwardly to position under the end 346 of the analyzing lever, by the spring 365, whereupon the spring 368 returns the anchor to tooth-engaging position. 60

Accumulator wheel mechanism

In the analyzing mechanism the head 251 has dropped into the recess for the digit 5 (Figs. 8 65 and 18) and when it is forced therefrom by the cam action of the recess, it will ride on the card until the digit 1 recess has passed. In the meantime by means of the rod 54 and the arm 352 the anchor 356 will be held away from the toothed 70 disk 361 until five of the teeth 360 have passed, when the anchor 356 will be released and catch the next succeeding tooth. When the numeral disk assembly has counted up to its limit, or "nine" the lug 376 on the carry and reset disk 363 75

will trip the transfer anchor 377 by forcing the upper arm 378 which carries the head 379, backward only a sufficient distance to permit the narrow portion 383 of the horizontal arm 384 to drop in behind the lower arm 385 of the anchor 377. The arm 384 is pivoted at 386 to the vertical arm 387, which in turn, is pivoted on the shaft 388, and the arm 384 is urged upward by the spring 389, one end of which is fastened to each of the arms. After the narrow portion 383 has dropped in behind the arm 385 and is occupying the notch 390, both of the arms 384 and 387 will be pushed forward by action of the cam 391 of the cam wheel 392 acting on the cam 393 on arm 387, which action forces the upper end of the transfer anchor 377 backward to engage the stud 394 which is on the next anchor 356 to the right, and allows a wheel to revolve until the head 358 catches the next on-coming tooth 360, which, when the first and second wheels from the left are considered and the first has added up to its capacity, or "nine", "one" will be transferred to the second wheel, to make a total of "ten". The cam wheel 392 is preferably made up of a series of disks each having one cam 391 thereon, there being a cam 391 for each set of arms 387 and each anchor 377. When these disks are assembled on their shaft they extend entirely across the machine, and indeed, the whole assembly then resembles more closely a shaft having a series of cams on its periphery and the disks are merely described as wheels because they constitute what might be regarded as a series of wheels side by side in compact formation. The cams 391 are progressively offset so that their action will take place only during the period of accumulative transferring. These disks are rigid on the shaft 394a which seats in the open end bearing 395 of the standard 396 which is secured to the block 397 by means of suitable screws 398. Extremities of the shaft 394a turn in the side plates 55 and 56. The arms 387 and 384 are held back against the cam wheel 392 by the spring 399, one end of which is fastened to the cross member 400 and the other end to the arm 387 at 401. Until the arm 385 of the transfer anchor 377 has been pushed forward, the narrow portion 383 of the arm 384 will ride under the lower end of the arm 385 without any definite action taking place, but when the portion 383 has dropped into the notch 390 it has assumed the position shown in dotted lines (Fig. 19) and will move the anchor 377 to its new position, or the position shown in dotted lines, but continued forward motion of the arm 384 brings the inclined portion 402 against the roller 403, which action lowers the portion 383 so that it starts to ride on the lower end of the arm 385, consequently discontinuing the forward movement of that arm and permitting both of the anchors to resume their normal positions through action of the springs 368 and 381. This is timed with the action of the cam wheel 392 so that the anchor 356 will permit only one tooth 360 to pass under it before it returns to its normal position, and at the same time the portion 383 will be placed in proper position for the start of a new cycle, or in the position shown in full lines in Figures 18 and 19. The shaft 388 is located in the cross member 404 which also acts as a brace for the machine. The numeral wheel assemblies are loosely held on the shaft 364 which is mounted in the open end bearing 406 of the standard 407, which standard is secured to the cross member 408 by means of screws 409. One

of the screws 409 at approximately the center of the machine, also holds the ribbon guide 410.

Resetting mechanism

The next action to take place, best shown in Figures 20 and 21, is the printing of the totals that have been registered by the numeral wheels, but it is deemed preferable not to explain the working of the mechanism involved in that function at this point, but to describe the mechanism for resetting of the counters after a print of the totals has been taken and by which the various elements are placed in proper position for a new run of cards.

The resetting operation may be accomplished in one revolution of the numeral wheel assemblies, and by revolving them in their normal or tabulating direction which is always forward or toward the operator as contrasted to the reverse direction, which is the usual procedure. This eliminates the necessity of the elements required for a reversing mechanism, and in addition, the resetting is accomplished in a much shorter time and with greater expedition than heretofore. There is a thumb piece 96 on a lever 416 preferably located on the left side of the machine which, when pressed, allows the elements shown in these two figures to be set in motion for the purpose of actuating the elements that actually perform the resetting operation. In Figure 20 the parts are shown in their normal positions, that is, the positions they take when the tabulation is being done and prior to the printing and reset operations. The lever 416 is held normally raised by spring 417 and rocks on the pin 418, and the downward movement of its arm 419 which takes place in the opening 414, in the base A is limited by a stop pin 420 engaging the upper surface of the base adjacent the opening. The rear arm 419 has at its end a catch 421 for engagement with the projection 422 of the dog 423 mounted on pivot pin 424 carried by arm 425, which as shown best in Figure 20a, is a part of the eccentric 434 keyed to the normally non-rotating shaft 101, and consequently both the disk 45 and arm revolve with said shaft at such times as the shaft is revolved. Adjacent this disk and mounted on the shaft 101 is the clutch disk 429 which is fast to a sprocket 430, the disk being provided with notches 428 for the reception of the tooth 427 of the dog 423 at the proper time to effect a joint movement of the disk and dog carrying-arm 425. As shown in Figure 20, the tooth 427 is held out of the notch 428 of the clutch disk by the catch 421 of the lever 416, in which position, obviously, the clutch disk is independent of the dog-carrying arm.

When the thumb piece is pressed it releases the dog 423 thereby permitting the tooth 427 to drop into one of the notches 428, which action is assured by the spring 432 (Fig. 21), which spring is attached by the screw 433 to the arm 425 and presses on the projection 422 on the dog, thus forcing the tooth 427 into one of the notches. The sprocket wheel 430 (Fig. 20a) which is fast to the clutch disk 429, is, as intimated, loose upon the normally non-rotating shaft 101. Fast upon this shaft is the eccentric 434 which eccentric, as we have seen, has integral therewith the arm 425, which arm in turn carries the pivoted dog 423 whose lower end has the tooth 427 adapted to enter one or the other of the notches 428 of the clutch disk 429, when released by a thumb piece 96 for actuating the mechanism for taking a print—all as will presently more fully appear.

The upper end 437 of the arm 435 is in engagement with the arm 438 of the bell-crank 94 when the eccentric 434 is in its lowermost position, as shown in Figure 20. The numeral 436 designates 5 a block against which the arm 435 slides in its up-and-down movement in the actuation of the bell-crank 94, which, during such movement, is rocked upon the reduced end 444 of a cam 455 which extends entirely across the machine with 10 its reduced ends supported in suitable bearings in the opposite side plates of the machine. Just within the bell-crank and keyed to the reduced end of the cam, which reduced end becomes a short shaft, is a gear wheel 445 which meshes 15 with the idler gear 446 mounted on a stud shaft 446a on the side plate 55, which in turn meshes with the gear 447 keyed to the reduced and cylindrical end 448 of the cam 456, which cam is, as shown, semicircular in cross section (Figs. 18 20 and 19). The bell-crank lever 94 is urged and held in the position shown in Figure 20 by a spring 440 with one end secured to the bell-crank arm 442 at 443 and the other end to the side plate 55 at 441. The movement of these gears 25 and cams is oscillatory.

Referring to Figures 21 and 22, when the finger 435 is raised it rocks the bell-crank 94, thus turning the gear 445 on shaft 444 and cam 455, the said gear turning the idler gear 446, which in 30 turn turns the gear 447 and consequently the shaft 448 and the cam 456, the cam being on or a part of the shaft 448. The shaft and cam are turned in a forward direction by means of the crank 94. The forward edge 457 of the cam 456, bearing on the rear arm 355 of the anchor 356, releases the head 359 from the tooth 360, and when the release occurs the friction clutch, previously referred to, takes hold and thereby revolves the disk assembly with it. As long as the head 40 359 is held free of the teeth the disk assembly would continue to revolve were it not for the fact that on the disk 363 is the tooth 376 (Figs. 19 and 22) in whose path of rotation is normally positioned the head 379 of the transfer anchor 45 377, and the head being held forward through the action of the cam head 458 of the cam 455 taking the position shown, under the arm 459, thereby locking it in this position, and as the shaft and the wheels continue to rotate in their 50 normal direction (forward) the tooth 376 contacts with the head 379 and stops the disk assembly. Due to the accumulating operation, different numerals will be in printing position at the start of a reset movement; hence the lug 55 376 on the different wheel assemblies will be at a different point in their paths of rotation, but as a lug 376 and head 379 engage, that particular wheel assembly will be stopped until finally all the wheels have been stopped at the same relative 60 position. The elements are arranged and timed so that when the lugs 376 are held by the heads 379 the zeroes of the wheels 362 will be at about the point indicated by the numeral 460. When the bell-crank 94 starts its reverse stroke the 65 cam 456 releases the arm 355 allowing the head 359 to take its normal position behind the tooth 360 and the cam 455 allows the arm 549 to release the head 379 from holding the lug disks, the lug 376 allowing the digit 460 to assume the 70 position at 462. The arm 384 is allowed to return to its normal position by the continued movement of the cam 455, thus permitting the narrow portion 383 to rest on the arm 385.

Reverting to Figure 21, it will be seen that 75 there is no positive connection between the bell-

crank 94 and the elements located below it; hence a means is provided whereby the reset operation may be accomplished without resorting to the thumb piece 96. This may be done by merely pulling forward on the handle 95 and letting it 5 return to its normal position, it being understood that when the pull is made upon the handle it is in the position shown in Figure 20. A hanger for supporting the shaft 101 is indicated by the numeral 463. This shaft is rotated by means of 10 the sprocket wheel 430 thereon and has the sprocket chain 464 connecting it with the sprocket wheel 465 to which power is supplied by the sprocket wheel and chain 466 and 466a, both of the sprocket wheels being rigidly fastened on 15 the same rotating shaft 550. Mounted on the shaft 101 just inside the plate 1 of Figure 2 is a sprocket wheel 101a with a chain 101b leading down to a sprocket on the shaft of a suitable motor, and on the same motor shaft there is 20 another sprocket around which runs a chain 466a, which chain runs over the sprocket 466, on the shaft 550, these chains and sprocket serving to transmit power from the motor for the operation, through other chains, sprockets and 25 gears, for the whole machine.

Printing mechanism

There is a rockable section 467 which pivots on the shaft 101 and encompasses the elements 30 carried by the shaft; the printing mechanism; the ribbon and paper-feeding mechanisms, the first mentioned of which will now be described.

A cam 468 (Fig. 21) extends for practically the entire width of the machine and may be of solid 35 construction, or it may be in sections, and has a sharp drop or cam head 469. This cam is mounted rigidly on the shaft 470, and at the right-hand end of said shaft is a sprocket 470a opposite a sprocket wheel 470b on the shaft 101. 40 These sprockets are connected by a sprocket chain 470c and are thus made to rotate in unison, and being of the same ratio the shafts will be rotated together (see dotted lines Fig. 25). The numeral 472 designates the printing hammer provided 45 with the hammer head 473. This hammer rocks on the shaft 474 and has a downwardly extending arm 471 that rides on the cam 468 and thus holds the head 473 in its rearward or normal position (Fig. 21). The hammer is further provided with 50 a forwardly extending arm 475 to which is attached the lower end of a stretched spring 476, the other end of which is attached at 477 to the cross piece 482. The cam has a set-up drop 478, and when this drop passes the lower extremity 55 of the arm 471 the action of the spring will suddenly pull it into the drop, thus projecting the hammer head against the paper 479 to take a print of whatever character is at the point 462 on a numeral wheel assembly, a printing ribbon 480 60 being interposed between the paper and character. As the arm 471 leaves the drop 478 and rides on the outer rim of the cam, the hammer head will be moved from its printing position, as shown in full lines in Figure 21. The movement 65 of the parts just described—that is, the printing elements—are synchronized with the reset elements previously described so that the printing takes place just prior to the reset operation and is completed very quickly by means of the sudden 70 drop 478 and the comparatively strong spring 476. The comb 481 attached to the cross piece 482 has recesses 483 therein to guide the hammers 472, there being a recess for each hammer. The cross plate or paper guide 485 is provided with the clear- 75

5 ance recesses 484 so that the plate will not interfere with the action of the hammers. The two dotted lines *a* (Fig. 21) of the drop 478 indicate the position of the cam 468 and the arm 471 before the thumb piece 96 has been pressed, and immediately thereafter, the space between them showing the short distance that the cam 468 travels in order to take a print. There is a means provided for holding out of action any of the printing hammers that may be desired, and the means here shown is not claimed in this application. On the under side of the cross member 486 (Fig. 20) is detachably secured a removable retaining piece 487 having at its upper end a short overhanging ledge 488 approximately of the width of the hammer arm 475. This piece may be pushed up between the rear ends of any of the hammers and moved to the right or left so that the ledge 488 rests on the end of any selected hammer arm 20 475, after the hammer head has been manually pulled forward and then released. This will move the lower arm 471 of the particular hammer to be temporarily dispensed with, out of contact with the cam 468 and thus prevent it from operating. This is done when it is expedient to have 25 separate groups of numeral wheels composed of any desirable number of wheels to conform to the number of group columns of the cards, the groups having different numbers of columns and 30 there being an active wheel for each column in each group. The retaining piece 487 may be formed to hold out a plurality of adjoining hammers by making it longer and placing it on the cross member 486 at either side of the machine 35 and sliding it over the arms 475 of whatever hammers are desired to be held out.

40 Referring now to the mechanism for operating the ribbon spools 490 and 491 (Fig. 1) there is a vertically movable actuating arm 492 (Fig. 20) for the purpose of turning both the ribbon spools and also the paper roll. It is guided at the bottom by means of a slot 493 working on a headed pin or screw 494, and there is a portion 495 having an elongated opening 496 therein in which 45 rides a cam 497 fastened on the shaft 470. At a point on the arm 492 convenient for operation of the ribbon spools, a pawl 498 is pivoted as at 499, the lower arm 500 of the pawl having one end of a spring 501 attached thereto, the other end of the spring being attached to the side plate 51 at any convenient point as 502 for the purpose of holding the head 503 in contact with one of the teeth 504 of the ratchet wheel 505 that rotates the shaft 506, and in order to insure that the wheel 505 will be turned just the proper distance, a flat spring 507 is fastened to the cross member 486 in any convenient manner, such as by the screw 508, the upper end 509 of the spring putting pressure on the ratchet wheel and preventing any 55 retrograde movement thereof. The shaft 506 which extends entirely across the machine also carries the beveled gear 510 (Fig. 21) which meshes with another beveled gear 511 on the shaft 512 that turns and supports the ribbon spool 491, the shaft being held in vertical position 60 in a recess in the cross piece 482 and a retaining piece 513. The shaft 506 extends across the machine to motivate the spool 490 when the ribbon feed has been reversed to that spool. There is a slot 514 in the cross piece 482 (Fig. 20) through 65 which the upper part of the arm 492 passes and is guided. Near the upper end of the arm 492 a cam 515 is provided which has a flat side 516 which bears against the rear edge of the arm and against 70 which the arm slides, the cam being adapted to

75 be turned by the handle 99 (Figs. 1 and 2) and when so turned will rock the arm 492 on the fulcrum screw 494, thus moving the head 518 away from the teeth 519 of the ratchet wheel 520, which wheel is fast on the shaft 521, as is also the paper roll 69. As previously explained, the shaft 470 80 is synchronized with and driven by the shaft 101 so that they each make one complete revolution when the thumb piece 96 is pressed, as before stated. The cam 497 raises the arm 492 the proper distance to enable the head 518 of the arm 492 and the head 503 of the pawl 498 to catch the oncoming teeth of the two ratchet wheels 520 and 505, and it then lowers the arm to turn each of the wheels the space of one tooth. This 10 action turns the ribbon spool and the paper feed roll that distance. To permit the forward movement of the arm 492 there is sufficient clearance in the cross piece 482, as indicated at 514 and 15 523.

20 The pivoted section 467 is arranged to be released and swung forwardly from the main part of the machine, thus permitting full view of the printing that has been done and ready access to the paper for any desirable adjustment 25 thereof. The left and right-hand side plates 71 and 72 (Figs. 1 and 2) have pivoted near their upper ends a cross rod 68 which preferably extends through the plates and carries on the outside thereof the latches 62 and 63 which are 30 rigidly fastened to the rod 68, and, when either or both of the thumb pieces 60 and 61 are pressed, two separate movements will be performed. First, the rear ends 66 and 66a (Fig. 20) will be raised from the retaining pins 67 and 35 67a to assume the position shown in dotted lines, thus removing the catch 530 from the retaining pin 67a and when this release takes place the entire portion 467 may be swung to the position shown in dotted lines in Figure 25. The side 40 plates 71 and 72 have rearward extensions 531 and 532, and they are pivoted on the shaft 101. The second movement consists of removing the paper retaining rollers 533, 533a and 533b (Fig. 1) away from the paper roll. The manner in 45 which the second movement takes place is more clearly shown in Figures 23 and 24 which will now be described. In Figure 23, the rear end 66a of the latch 63 is shown in two positions, the lower one being at the end of the first movement which releases the catch 530 from the retaining pin 67a, the upper position being that at 50 the end of the second movement which has removed the rollers 533, 533a and 533b away from the paper 479 to the position shown in dotted 55 lines. The roller is held in the fork 535 and turns on the pin 536, the fork being attached to or integral with the sleeve 537 which is loose on the rod 68. In order to keep the sleeve from longitudinal movement on the rod 68 there is a 60 collar 538 (Fig. 24) rigidly attached to said rod at one end of the sleeve and another collar 539 similarly attached to the rod at the other end, the latter having a lug or extension 540, the extension being positioned in the recess 541 of 65 the sleeve, the lug being smaller than the opening, as shown in Figure 24. This difference in size between the lug and recess permits lost motion, so that when the rod 68 is turned enough to bring the front of the lug 540 into engagement 70 with the sleeve at the front of the opening 541, the catch 530 will have been raised to the lower dotted line position and clear of the pin 67a, and further movement of the rod will cause the sleeve to turn with it, moving the fork 535 and 75

rollers away from the paper. Provision is made for returning these parts to their normal positions by means of the spring back plunger 98 (Fig. 2) which is positioned in the sleeve 97 located under the thumb piece 60, there being a similar arrangement on each side.

The paper 479 passes by the printing character 462, and has interposed between it and said character the printing ribbon 480, so that 10 when the hammer strikes the paper directly in front of the character the paper will receive the desired impression after which the paper continues on up over the paper feed roll 69.

In Figure 25 the rockable section 467 is indicated in dotted lines wherein it has been swung away from the body of the machine. In this figure it can be seen how the side plates 71 and 72, having the rearwardly extending portions 531 and 532 pivot on the shaft 101 which extends 20 through openings in these side plates and has its bearings in the sides of the base A.

The ends 91 of the push rods 54 are held in the upper ends 351 by means of the cross member 58 which is removably positioned on the 25 upright 57. However, the main purpose of the cross rod 58 is to prevent the ends of the push rods from becoming accidentally dislodged from their recesses in the rocker arms 352, and the rod 58 is also made readily removable for the 30 purpose of having ready access to the push rod ends to rearrange them for different tabulating set-ups. When it is desired to move any of the rods 54 it is only necessary to remove the screws holding the upright 57 which will allow the cross 35 rod 58 to be raised.

The sprocket assembly 59 (Figs. 1 and 25) is composed of the sprocket chain 549 which runs over a sprocket 549a fast to the shaft 550, and another similar wheel 549b fast on the shaft 40 394a which has bearings in standards 552 secured to the base A.

The cam shaft 394a which extends entirely across the machine is enlarged at one end, and just beyond the side plate 56 it is provided with 45 a gear 553 which is so mounted on said shaft as to turn therewith (Fig. 25). This gear meshes with an idler gear 553a mounted on a stub shaft 553b on plate 56, which gear in turn meshes with another idler gear 554 also mounted on 50 a stub shaft carried by the side plate, and this gear in turn meshes with a gear 555 which is fast on the rotatable shaft 364, which shaft carries the numeral wheel assemblies.

Pressing on the thumb piece 560 of the lever 55 561, pivoted at 562 on the side plate 1, starts the motor that drives the machine. This lever carries, about intermediate of its ends, a roller 563 which works against the upper end 564 of the lever 565, which is pivoted at 569 also to 60 the side plate 1. The lower end 570 of this lever extends into a pin-guarded recess 571 in a bifurcated head 572 carried by the slide rod 573 which has a bearing in a bore in a block 577a suitably secured to the under side of the base A. A spring 566 normally urges the thumb piece 65 lever upward, the spring having one end fastened at 568 and the other to a support 567.

The downward movement of the thumb piece 560 causes the roller 563 to force the handle 70 564 rearwardly, rocking the lever 565 on its pivot 569, which movement causes the lever end 570 to move the rod 573 (Fig. 26) forwardly to the dotted line position, in which position the pin 574 carried by the rod will be in the path 75 of movement of an elongated lug 575, integral

with a collar 576 on the shaft 101. The shaft revolves only when the reset mechanism is operated, and then makes but one revolution during which the pin will be engaged by the lug to force the rod to its circuit-breaking position,—best 5 shown in full lines.

The detail mechanism for the actions just described is illustrated in Figure 27, which is a top view partly in section and partly in elevation. The rod 573 that moves back and forth in bore 10 577 in bearing block 577a has a depression 578 therein for the reception of a ball 579 which, when the lever is in its rearmost position, rests in said recess, on top of which ball is another ball 580, the two resting in the recess 581, the 15 upper ball being adjacent to a spring or flexible element 582 which has one end 583 fastened to the block 577a and the other end carries a button 584 of non-conducting material. It will be seen that as the rod 573 is moving forwardly, 20 the ball 579 will ride up out of the recess 578 thereby raising the spring 582 through the other ball 580, which forces the terminal 585 to contact the terminal 586 at the point 587 which will complete a circuit, thus allowing current to flow 25 through the wires 588 and 589 to operate the motor 590. At 591 is indicated a fuse and at 592 a manually operated switch. The terminals 585 and 586 are fastened conveniently by the screws 593 and 594 to a block of non-conducting 30 material. The collar 576 having the lug 575 thereon is below the block 577a and in such position that the pin 574 carried by the rod will be engaged at appropriate times by the lug.

In Figure 28 the paper roll is shown partly 35 broken away and having near its ends roughened portions 601 and 602, and at one end there is the usual ratchet 520 through which the roll is revolved to feed the paper, and at its other end there is a disk 603 having numerous circularly 40 arranged depressions 604 therein, the recesses cooperating with a ball 605 normally urged into one or the other of the recesses by spring 606 confined in the opening 607 in the side support 12; the arrangement being such as to yieldingly 45 hold the roller at any desired printing point. The roll shaft 521 is suitably mounted in the side supports 71 and 72.

Referring particularly to Figure 18a, the card 249 is such as controls the operation of the machine. On this card only enough columns or groups of numerals are shown to make clear the reason for the particular push rod arrangement or "set-up" shown in Figure 1, wherein it will be noted there are five push rods 54 on the left side 55 of the machine and three of such rods on the right, each connected at its forward end to its appropriate rocker arm 352. In column a' of the card the numerals appear from 1 to 9, arranged in rows of five figures each, with certain 60 of the numerals punched out, and, in column b wherein the numerals are similarly arranged as to progression, there are rows of three numerals each with certain numerals punched as in column a'. A card is fed through the machine, lower 65 edge c first, thus bringing the five numeral group column a in position to operate, by reason of the perforations therein, upon one or the other of the push rods 54 in the "5" group of rods on the left; whereas the perforations in the "3" group 70 column b are brought in position to operate on the push rods on the right as each perforation, in its time, becomes available to the head 251 (Fig. 18) to permit it to pass through into the appropriate cam recess 5' in the analyzing roll 5 pre- 75

paratory to the virtually instantaneous operation of the analyzing lever 25°, whereby, through the mechanism interposed between said lever and the numeral wheel assembly the latter is controlled.

As intimated, the card 249 shown is not complete, and it will be understood that a card so columnized would seldom be used, the used card containing columns or groups extending entirely across its face, the groups being headed by appropriate intelligence or intelligible data having reference to the things to be tabulated or enumerated either in code or otherwise.

The final make-up or construction of the machine contemplates a push rod for each analyzing lever 250, each rocker arm 352, and for each numeral wheel assembly; but all of these push rods are not necessarily connected with the rocker arms at the same time—only so connected according to a particularly desired group arrangement in accordance with a column arrangement of the record card. Obviously, these push rod groups may be variously arranged, as for instance in a case where, in a particular card column the numerals appear in rows of eight, there will be a group of eight rods for the operating eight "active" numeral wheel assemblies, with such additional number of auxiliary accumulator wheels as may be desirable to take care of the accumulated total of the active wheels.

When a push rod 54 is connected with a rocker arm 352 and operated by an analyzing lever 250 to permit a numeral wheel assembly to be operated, that wheel may be called active, and for the number of active wheels there may be a number of adjoining wheels (not directly connected with the push rods) which may be called, as stated, auxiliary accumulator wheels when used as such, and it will be understood that any and all of the accumulators may be turned into active wheels or vice versa, accordingly as the group arrangements of the push rods may require for the tabulation of various card group arrangements. The auxiliary accumulators carry on the work of the active wheels in that the numeral totals of the active ones are accumulated or transferred to the auxiliaries. The auxiliaries will be varied in number according to the nature of the thing or article designated by the card perforation: for instance, when the total number of acres are only to be considered there would be fewer accumulators required than for the tabulation of bushels of wheat, etc. There is a rocker arm 352 for each numeral wheel assembly and by numeral wheel assembly I mean that each numeral wheel is made up compactly of three major portions: the toothed disk 361; the numeral-bearing disk or wheel 362; and the lug-bearing disk 363, in laminated arrangement, there being a central space within the disk 362 for the reception of a suitable friction clutch arrangement by which the assembly may be revolved with the shaft 364 or not, as the exigencies of the operation may require, as for instance, when the assembly is held from revolution by appropriate devices forming constituent parts of mechanism closely associated with the wheel assembly operation. The clutch mechanism which I prefer is that shown in my U. S. Letters Patent No. 1,516,772.

At numerous points throughout the specification and claims I refer to various elements in the singular number, such as the push rod 54; analyzing lever 250 and many other elements because it is believed to be obvious and is also well

known in the art that a plurality of such elements must be utilized and their number is governed solely by the requirements for the particular machine. Each of the numeral or accumulator assemblies 362 must have its own individual 5 chain of elements which are really duplications. There are other instances where an element or assembly is present on one side of the machine and has a duplicate element or assembly on the opposite side of the machine, such as in the case 10 of the latches holding the swinging portion 461, and the actuating means such as the barrel 97 and plunger 98 for holding the latches in their normal positions.

I have spoken of "numeral wheel assemblies" 15 and explained that the term is used because in this particular case the assemblies are made up of three disks compactly assembled and moving together, each disk having its particular function, and each constituting in the concrete a wheel; 20 therefore the term is not to be considered as used in a restrictive sense, and may for the purposes of this invention, be considered to comprehend the terms "wheels", "numeral wheel" or "disk", which are to be considered equivalents in the 25 broader sense.

I claim

1. In a perforated record-controlled tabulating machine, in combination, a rotating power transmitting analyzing element formed with means 30 for actuating an analyzing device, an analyzing device having a portion formed to be operatively engaged by the actuating means of the power transmitting element through perforations in a record to actuate the analyzing device, and a 35 movable member arranged to be moved by said analyzing device when said device is actuated by the power element.

2. In a perforated record-controlled tabulating machine, in combination, a rotating power transmitting analyzing element formed with means 40 for actuating an analyzing device, an analyzing device having a portion formed to be operatively engaged by the actuating means of the power transmitting element through perforations in 45 a record to actuate the analyzing device, and a reciprocable actuating element arranged to be moved by said analyzing device when said device is actuated by the power element.

3. In a perforated record-controlled tabulating 50 machine, in combination, a rotatable power transmitting analyzing means formed to actuate an analyzing device, an analyzing device, said device having a portion to be engaged by the power transmitting means through perforations in a 55 record to positively actuate said device, and means moved by said analyzing device when said device is actuated by said means.

4. In a perforated record-controlled tabulating 60 machine, the combination of a rotatable power transmitting analyzing element provided with recesses, each having a cam-like wall, an analyzing device formed to engage in said recesses through perforations in a record, and positively actuated by said wall when said power transmitting element is rotated, and a movable member arranged to be moved by said analyzing device when the device is actuated by the power transmitting element.

5. In a perforated record-controlled tabulating 70 machine, the combination of a rotatable power transmitting analyzing element formed with circumferentially arranged cam means for operating an analyzing device, an analyzing device formed to engage ~~said~~ 75 cam means through

perforations in a record and be positively actuated by said means, and means moved by said analyzing device when actuated by said power transmitting element.

5. 6. In a perforated record-controlled tabulating machine, in combination, a power transmitting analyzing roll, means for rotating it, and means for continuously feeding perforated records past said roll in juxtaposition thereto, said roll being provided with a plurality of circumferentially arranged cams available through a perforation in a record, an analyzing device having a head arranged to be projected through said perforation to cooperate with a cam on said power roll whereby to operate the analyzing device when the roll is rotated, and means operated by said analyzing device when said device is actuated by said roll.

7. In a perforated record-controlled tabulating machine, in combination, a power transmitting analyzing element, means for rotating it, and means for continuously feeding a perforated record past said element in juxtaposition thereto, circumferentially arranged analyzing device-operating means forming a part of said rotating power element, and engageable only through a perforation in a record, an analyzing device having a portion adapted to extend through a record perforation to cooperate with said device operating means of the power transmitting element, means moved by said analyzing device when actuated by said power transmitting element.

8. In a perforated record-controlled tabulating machine, in combination, a power transmitting analyzing roll, means for rotating it, and means for continuously feeding perforated records past said roll in juxtaposition thereto, said roll being provided with a plurality of circumferentially arranged cams available through perforations in a record, an analyzing device having a head adapted to be projected through a card perforation to cooperate with a cam whereby to operate the device when the roll is rotated, means operated by said analyzing device when 45 said device is actuated by said roll.

9. In a perforated record-controlled tabulating machine, in combination, a power transmitting analyzing roll having circumferentially arranged thereon spaced recesses, an analyzing device having a portion adapted to enter one or another of said recesses through a perforation in a record and to be forcefully expelled therefrom by the rotation of the power roll, and means operated by said analyzing device when said device is actuated by said roll.

10. In a perforated record-controlled tabulating machine, comprising two rolls one of which being a driven feed roll and having a plurality of recesses therein, the other roll having a plurality of grooves there-around, a plurality of pivoted analyzing devices, the heads of which are arranged for the reception in and expulsion from the recesses in the driven roll, the grooves in the other roll being arranged to receive said heads upon expulsion from said recesses, and a movable actuator member arranged to be actuated by the movement of the analyzing device, when the device is actuated by the driven roll.

11. In a perforated record-controlled tabulating machine, in combination, a rotating power transmitting roll having recesses therein, each recess having a cam-like wall therein, an analyzing device, means for urging said head into a recess through a perforation in a record, the cam-like walls of the recesses serving to force

said head from a recess upon the rotation of the power roll, and a movable member actuated by the analyzing device when said device is actuated by the power roll.

12. In a perforated record-controlled tabulating machine, in combination, a power transmitting roll having a plurality of recesses therein arranged in longitudinal rows and circumferential columns, each provided with a cam-like wall, a plurality of analyzing devices having heads arranged to simultaneously enter any number of the longitudinally arranged recesses when said recesses are available through a record perforation but only one of the circumferential recesses at a time, and to be forcefully expelled from said recesses by the cam-like walls thereof, upon the rotation of the power roll, and a movable member arranged to be moved by each of said analyzing devices respectively when said devices are actuated by the power roll.

13. In a perforated record-controlled tabulating machine, in combination, a rotating power transmitting element formed with means for actuating an analyzing device, said means being arranged in longitudinal rows and circumferential columns, an analyzing device having a portion formed to be operatively engaged by the actuating means of the power element through columnized perforations in a record to actuate the analyzing device, and a movable member actuated by said analyzing device when said device is actuated by the power transmitting element.

14. In a perforated record-controlled machine, in combination, means for actuating elements of a tabulating machine, including a power transmitting analyzing roll having recesses therein, each recess having a cam-like wall, an analyzing device having a head formed to engage in said recesses through perforations in a record, the cam-like walls of the recesses serving to actuate the analyzing device when the power transmitting roll is rotated to cause said device to actuate said means.

15. In a perforated record-controlled tabulating machine, the combination of a plurality of rolls, a no-card lever having one end extending between said rolls, means arranged to urge said lever to normal no-card position, an analyzing device and means for holding the said analyzing device in inoperative position and controlled by 45 said no-card lever when the no-card lever is in normal or no-card position.

16. A no-card control for perforated record-controlled tabulating machines, including two rolls, one above the other and each having an annular groove therein, the grooves being in vertical alignment with each other, a no-card lever having an end extending between said rolls and positioned in said grooves, means arranged to urge said lever to normal no-card position, an 55 analyzing device and means for holding said analyzing device in inoperative position and controlled by said no-card lever when the no-card lever is in normal or no-card position.

17. In a perforated record-controlled tabulating machine, in combination, a plurality of rolls, a rockable no-card lever formed with a horizontal arm and a vertical arm, means for urging said lever to normal no-card position, an analyzing device, a latch means arranged to engage the vertical arm of the no-card lever to lock it in no-card position when the analyzing device is in 70 inoperative position.

18. In a perforated record-controlled tabulating machine, in combination, a rotatable power 75

transmitting roll having recesses therein, a pivoted analyzing device one end of which is arranged to engage a recess through a record perforation and be expelled therefrom, the action of entrance and expulsion serving to rock said device, a push-rod having one end normally in the path of movement of the other end of the analyzing device, a rockable bar having a portion arranged to engage the push-rod to move it from the path of movement of the analyzing device to suspend the operation of the rod.

19. In a machine of the character described, in combination, a plurality of rolls, one of which is a power transmitting roll, an analyzing device actuated by the power transmitting roll, means actuated by the analyzing device to control movements of a tabulating mechanism, and means operating in the absence of a record card to suspend the operation of the first mentioned means.

20. In a perforated record-controlled tabulating machine, in combination, a rotatable power transmitting element, a plurality of rockable analyzing devices actuated by said element through perforations in a record, push-rods cooperating with the analyzing devices to be actuated by said devices when said devices are actuated by said element, and means operating upon all the push-rods and upon all of the analyzing devices to hold them in inoperative position during an interval between cards.

21. In a perforated record-controlled tabulating machine, in combination, a rotatable power transmitting element, a plurality of analyzing devices operated by said element through perforations in a card, push-rods actuated by the analyzing devices, means for simultaneously depressing all the push-rods, means operating upon the analyzing devices to simultaneously bring them into engagement with the tops of the push-rods when said rods are in depressed inoperative position, and means for locking said levers and rods in such inoperative position at intervals between card runs.

22. In a perforated record-controlled tabulating machine, in combination, a rotatable power transmitting element, a plurality of analyzing devices operated by said element through perforations in a record, push-rods actuated by the analyzing devices, a rockable arm arranged to simultaneously depress all of the push-rods to take them out of the path of operative movement of the analyzing devices, but to permit said devices to engage the tops of said push-rods while in depressed position, a reciprocable plate carried by the rockable arm and means to reciprocate the plate to lock the analyzing devices in inoperative position at intervals between card runs.

15 23. In a machine of the character described, the mechanism as claimed in claim 22, characterized in that the reciprocable plate is positioned in a slot in the rockable arm and connected with a cam-operated oscillating arm.

20 24. In a perforated record-controlled tabulating machine, in combination, a rotatable power transmitting device, a plurality of analyzing devices operated by said power device, means moved by said analyzing devices when actuated by the power device, and means for controlling the movements of the analyzing devices in the absence of a record whereby said analyzing devices are held in inoperative position.

25 25. In a perforated record-controlled tabulating machine, in combination, a rotatable power transmitting element, a plurality of analyzing devices operated by said element through perforations in a record, push rods actuated by the analyzing devices, means for simultaneously depressing all the push rods, and means operating upon the analyzing devices to simultaneously bring them into inoperative position relative to the push rods, including a reciprocable plate associated with the push rod depressing means, and means for holding said plate in contact with the analyzing devices between card runs.

30 35 40 EUGENE M. LA BOITEAUX.
